ELECTRICAL APPLIANCE AND PLUG
THEREFORMichael W. McArdle, Chicago, Ill., assignor to
Chicago Flexible Shaft Company, Chicago, Ill.,
a corporation of Illinois

Application September 7, 1934, Serial No. 743,078

6 Claims. (Cl. 173—332)

This invention relates to connector plugs for electric appliances, and while the invention is of general application to plugs for electrical household appliances, the invention is herein shown and described for purposes of illustration in connection with an electric sadiron.

Electric current is supplied to the conventional electric sadiron and similar household appliances through a flexible cord attached thereto and this point of attachment has always given a considerable amount of trouble. However, when the irons were of low capacity, the trouble was not particularly difficult but with the advent of high capacity irons drawing in the region of 15 a thousand watts, the difficulty is much more serious. In the past, the iron has been provided with a pair of contact terminals projecting from the body of the iron and adapted to be received in a connector plug carried on one end of the 20 cord, the plug being capable of withdrawal from the terminals to separate the cord from the iron. However, when the plug is removed from the terminals there is a considerable amount of arcing between the terminals and the contact elements of the plug. This causes pitting and corroding of the terminal posts and of the contact elements so that in a short time the parts are not capable of making an effective contact. As 25 above mentioned, when the wattage of the irons was low this trouble was not particularly difficult but with the increased wattage in 1000 watt irons the arcing is much more severe and the pitting and corroding is increased.

Another source of difficulty to this type of 30 connection between the cord and the iron lies in the fact that the terminal posts are received in sockets of the plug formed by bronze contacts, the bronze contacts being used to secure proper conductivity. These contacts cannot be tempered and hardened as would be the case with 35 spring steel and, consequently, when the plug is pushed over the terminal posts the bronze contacts spread apart and do not again come together so as to grip the terminal posts tightly. 40 As a result, a certain amount of arcing normally occurs during the use of the iron. This is further aggravated by the fact that the plug is then loosely held on the terminal posts which allows a certain amount of movement of the plug as the 45 iron is moved about. It augments the arcing and further increases the difficulty from corrosion and from pitting.

The cord cannot be satisfactorily connected directly to the iron, that is, to the terminal posts of the iron because the heat of the iron is then

conducted into the cord, causing the insulation to be burned or otherwise depreciated to a point where the two cables of the cord come into contact or in such proximity that the cord becomes burned off or shorted.

With the above mentioned objections in view, I have aimed to provide a connector plug for connecting the cord to the appliance in such manner that the contact elements of the plug at all times firmly grip the terminal posts.

A further object of the invention is to provide a plug carrying means for normally securing the plug to the appliance to prevent frequent removal of the plug.

Another object of the invention is to provide a plug structure having means for preventing a considerable amount of the heat from the appliance from passing to the plug and thereby heating both the plug and the cord attached thereto.

Another object of the invention is to provide a plug having means for holding the same against movement with respect to the terminal posts so as to prevent arcing due to movement of the plug thereon during the use of the appliance.

A further object of the invention is to provide a plug having means for normally securing the plug on the iron against movement with respect to the terminal posts, the means being accessible for removal of the plug as required.

Another object of the invention is to provide a plug of generally improved design and function.

Other objects and attendant advantages will become apparent to those skilled in the art from the following description and the accompanying drawing, in which—

Fig. 1 is a side elevation partly in section;

Fig. 2 is a fragmentary rear elevation;

Fig. 3 is a section on the line 3—3 of Fig. 2, and

Fig. 4 is a section on the line 4—4 of Fig. 2.

The invention contemplates a plug of insulating material provided with means for spacing the end of the plug from the body of the appliance and means for holding the plug in fixed position with respect to the appliance, together with spring means for holding the contact elements or plug jacks in firm contact with the terminal posts of the appliance.

Referring to Figure 1, I have shown the invention in connection with a conventional electric sadiron having a body 6, a handle 7 secured thereto by means of handle straps 8 and 9, the handle being secured to the handle straps by means of a bolt 11, a temperature controlled lever 12 mounted on the body, and a heel rest 55

13 having a rectangular sleeve 14 for the reception of a cord plug.

The plug includes two insulating members 15 and 16 complementarily shaped and positioned 5 face to face to form a plug body. The member 16 carries a pin 17 receivable in an opening 18 of the member 15 to locate the two portions with respect to each other. The body has a pair of sockets 19 and 21 for the reception of jacks 22 10 and 23 presently to be described, the sockets being formed by recesses in the adjoining faces of the portions 15 and 16. The upper end of the sockets open into a chamber 24 shaped to receive the lower end of a spring element 25 surrounding 15 the cord 26 in the usual manner.

Jacks 22 and 23 are each formed of highly conductive material such as bronze and consist of two contact elements 27 and 28 having semi-cylindrical portions 29 and 31 for the reception of 20 terminal posts 32 and 33 of the sadiron. The contact elements are placed face to face so as to provide a more or less cylindrical surface for the reception of the terminal posts for maximum surface area therebetween. The upper ends of 25 the contact elements 27 and 28 are secured together by means of a screw 34 which also serves for the attachment of the individual cables 35 and 36 of the cord 26. The jacks 22 and 23 are of such size that the contact elements 27 and 28 30 come substantially into contact when the insulating portions 15 and 16 are in surface contact and have somewhat smaller inside diameters than the outside diameters of the terminal posts 32 and 33 so that when the terminal posts enter the jacks 35 the contact elements 27 and 28 are spread as well as the insulating portions 15 and 16 of the body.

Pressure is applied between the jacks and the terminal posts by means of springs 37 and 38 which span the edges of the plug adjacent the 40 lower end thereof, as best shown in Fig. 4. The springs are positioned in recesses 39 and 41 in the outer surface of the plug whereby to hold the portions of the plug together without bolts or screws and maintain the portions in registering 45 relationship. Thus, when the terminal posts move into the jacks, the contact elements 27 and 28 are spread, causing the plug to spread against the tension of the springs 37 and 38 whereby the springs urge the contact elements into gripping 50 contact with the terminal posts.

The springs 37 and 38 each carry a depending finger extending beyond the end of the plug, as shown at 42 and 43, the fingers being adapted to abut the body of the sadiron, as shown in Figure 1, to space the lower end of the plug from the body of the iron. This structure permits air to circulate between the end of the plug and the body of the iron, the air circulating around the terminal posts and serving to cool the same so 55 that only a limited portion of the heat of the iron is transmitted upward along the terminal posts and, as a result, the plug is maintained at a relatively low temperature.

The two insulating halves of the plug body are 60 held together at their upper ends by means of a collar 44 shaped to be received in an annular recess 45 at the upper end of the body. This collar prevents the two halves of the plug body from spreading at the top but permits the bottom end 65 to spread, as previously described. The collar 44 has a bracket 46 extending upwardly and outwardly so as to register with the end of the handle 7 and is provided with an opening 47 for the 70 reception of the bolt 11 so that the bracket is fixedly attached to the handle 7 and the handle

strap 9. The bracket and collar are so shaped as to apply a slight downward pressure on the top of the plug body urging the fingers 42 and 43 into contact with the body of the iron, whereby to fixedly secure the plug on the iron and prevent any tilting or weaving movement of the plug with respect to the iron. In this way, repeated withdrawals of the plug from the iron are prevented, the plug being attached in a semi-permanent manner to the iron. In service, this requires 10 the operator to disconnect the iron from the source of current supply at the opposite end of the cord 26, leaving the plug in position on the iron. However, when necessary, the plug may be easily and conveniently removed from the iron by 15 loosening the bolt 11 and withdrawing the plug from the terminal posts in the usual manner.

While the advantages of my improved construction will doubtless be apparent, I desire to direct particular attention to the following features:

The plug body is formed of two insulating complementary halves which are held together by means of spring clips which permit the jacks to be made somewhat smaller than the terminal posts which are received therein whereby the jacks may spread when the posts are inserted, the springs serving to cause the jacks thereafter to firmly grip the terminal posts. The plug is provided with fingers which serve to space the plug from the body of the iron to provide for the circulation of cooling air between the plug and the body of the iron, the air being circulated around the terminal posts. Means are provided for securing the plug on the iron in a semi-permanent fashion in such manner that the plug may be conveniently removed when necessary and yet may not be repeatedly attached and removed from the iron in the normal operation thereof. The attaching means acts to prevent weaving and tilting of the plug on the terminal posts when the iron is in service and holds the plug in such manner as to provide a fixed contact between the terminal posts and the plug jacks. The attaching means also serves to hold the body portions together at their upper ends and permit spreading of the portions at their lower ends against the tension of the spring clips.

While I have thus described and illustrated a specific embodiment of my invention, I am aware that numerous alterations and changes therein may be made without departing from the spirit of the invention and the scope of the appended claims, in which—

I claim:

1. A plug for use with electrical appliances having fixed terminal posts, comprising a body of insulating material formed of two substantially identical halves arranged face to face and having recesses in the faces forming sockets, plug jacks in said sockets for the reception of the terminal posts of an electrical appliance, and spring clips on the outer surface of said plug at one end thereof for preventing lateral movement of said halves and for urging the halves together to compress the jacks against the terminal posts, said springs carrying depending fingers for spacing the plug from said appliance.

2. A plug for use with electrical appliances having fixed terminal posts, comprising a body of insulating material formed of two substantially identical halves arranged face to face and having recesses in the faces forming sockets, plug jacks in said sockets for the reception of terminal posts of an electrical appliance, and spring

- clips on the outer surface of said plug at one end thereof for preventing lateral movement of said halves and for urging the halves together to compress the jacks against the terminal posts, 5 said springs carrying depending fingers for spacing the plug from said appliance, and means on the opposite end of said body holding the halves together when said halves are spread by insertion of terminal posts in said jacks arranged 10 for permanent attachment to the appliance for rigidly holding the plug in position on the terminal posts.
3. A connector plug for electrical appliances having fixed terminal posts, comprising separable body halves with interposed plug jacks at 15 one end and interposed terminal conductor wires emanating from the opposite end, means yieldingly urging the halves together at the plug jack end, means at the upper end of the plug holding 20 the halves together, the latter means having an extension adapted for attachment to the appliance for rigidly holding the connector plug in position with its jacks plugged onto the terminal posts.
- 25 4. A connector plug as set forth in claim 3, in which said plug holding means has a socket for reception of the upper end of the plug body halves for holding the upper end of said halves against separation and said extension is detachable from the appliance to permit removal of the plug from the terminal posts.
5. A connector plug as set forth in claim 3, including depending fingers on the plug jack end of the plug for spacing the plug away from the 5 appliance to allow air circulation between the appliance and said plugged end.
6. A connector plug for electrical appliances having fixed terminal posts comprising separable body halves with interposed plug jacks at 10 the lower end adapted to be plugged onto said jacks, spring clips on the outer surface of said body halves serving to yieldingly urge them together and by their contact with the interposed jacks to yieldingly compress the jacks against 15 the terminal posts, said spring clip having lugs projecting downwardly beyond the end of the plug body to hold the plug away from the appliance and allow air to circulate under the plug when it is plugged onto the terminal posts, and 20 means at the top of the plug for holding the halves together and permitting separation of the lower ends thereof against the pressure of said spring clips when said plug is plugged onto the terminal posts, said means having an extension 25 arm for rigidly but detachably securing the plug to the appliance to hold the plug permanently in position on the terminal posts.
